DESIGN FOR A SHOE SOLE

Application filed February 17, 1932. Serial No. 42,912. Term of patent 3½ years.

To all whom it may concern:

Be it known that I, JAMES E. DYER, a citizen of the United States, residing at Los Angeles, in the county of Los Angeles and State of California, have invented a new, original, and ornamental Design for a Shoe Sole, of which the following is a specification, reference being had to the accompanying drawing, forming a part thereof, in which drawing

Fig. 1 is a plan view of a shoe sole showing my new design.

Fig. 2 is a side view corresponding to Fig. 1.

I claim:

The ornamental design for a shoe sole, as shown.

JAMES E. DYER.
